(57) **CLAIM**

The ornamental design for a bed vacuum cleaner, as shown and described.

DESCRIPTION

FIG. 1 is a top perspective view of a bed vacuum cleaner, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

It is mainly composed of HEPA Filter, high-frequency tapping, vacuum motor, and visual trash can. It combines three functions of purple light, polaroid and vacuuming to absorb particles such as hair, pollen, dust, dander, etc. It is suitable for cleaning beds, sofas and other fabric products. The broken lines in the drawings illustrate the portions of the bed vacuum cleaner, which form no part of the claimed design.
